UNITED STATES PATENT OFFICE.

CHESTER I. WAGNER, OF NEW YORK, N. Y.

RECORD-FILING SYSTEM.

Application filed September 28, 1923. Serial No. 665,359.

This invention relates to systems for filing records, and is of particular utility when employed in connection with systems dealing with a multiplicity of units of subject-matter, such as the cards in an index, or the folders containing letters in a correspondence file, these constituting elements of the system to which additions are frequently being made of subject-matter units, singly and in groups, and also more extended additions of subject-matter units in orders, such additions being often of a character and extent which are indeterminate at the time of commencing the installation of the system, so that the system should afford provision for substantially infinite expansion, and should be sufficiently elastic in its basic principle not only to accommodate additions of all possible orders, but also to permit convenient accomplishment of all the deletions requisite to elimination of obsolete subject-matter.

Conventional filing systems ordinarily comprise also guide-members, interpolated among the subject-matter units to aid in filing and finding the units, and while the subject-matter units are more or less adventitious, their permanence as elements in the system varying according to the nature of their subject-matter, on the contrary the guide-members should constitute a perpetual element, the guide-members expanding in their aggregate quantity to meet the demands of convenience in filing and finding, as the quantity of units is increased.

These guide-members should be of such a character that this element of the system will not constitute a "set" which must be discarded in its entirety and replaced by a larger "set" to meet the demands of growth in the system, but can be expanded by the addition at any time of such a quantity of guide-members as the growth of the system requires at that time.

The guide-members should also be of such a character preferably that one or more of them can be withdrawn from any part of the system when not needed there, and can, if required, be used elsewhere in the system, and thus maintain the system in most convenient condition for current use, and free from deadwood.

So far as I am aware, the only system which meets the above requirements for a perpetual

and universal system of filing, to any practical extent, is that forming the subject of my copending application for United States Letters Patent Serial No. 144,260, filed Jan. 24, 1917, and it is to the improvement of the latter that my present invention is particularly directed, although I contemplate the utilization of my improvements in any field for which they are adapted by their nature, respectively.

In the system forming the subject of my aforesaid application, Ser. No. 144,260, the several units of matter to be filed in filing devices of all kinds are provided with numerical designations respectively related to the conventional verbal designations of said units, and coded therefrom in such a manner that no separate record, cross-index or like record is necessary to identify the numeric designation with the alphabetic, geographic or subject designation under which the matter is commonly identified, and in accordance with an important feature of my aforesaid invention these numeric designations are preferably arranged to remain on the units of matter in juxtaposition with the ordinary designations, to facilitate location of the matter for reference, filing and finding.

The aforesaid system is expansible to an unlimited extent by the interpolation of additional units, and orders of units, of matter, and is likewise contractible, and comprises also a similarly expansible and contractible system of guide-members and sub-guide-members for interpolation with the units of matter, said guide-members bearing numerical indicia also coded from the designations of said subject-matter, the subject-matter being therefore indexed by the guides in such a manner that the matter can be easily located for reference, filing and finding.

In the installation of the aforesaid system, it is unnecessary to ascertain or forecast the amount of matter to be filed therein eventually, nor is the user obliged to place the whole system of guides in the files at the beginning of the filing period.

Another highly important object accomplished by the aforesaid system is the organization of tabs bearing the indicia, on the guide-members, in such alignment as to present the decimal components of the filing numbers in successive overlapped or off-set

positions readable as a whole to indicate the exact position of any single unit or group thereof, and in the same manner to index further an order, a group or a subdivision of 5 units, by tabs aligned differently, or bearing indicia with differentiating characteristics, in connection with similar decimal components coded from secondary designations, such as given names or initials.

- 10 The foregoing features of my aforesaid system have been made the subject of generic claims in my aforesaid application, to which reference may be had for a more extended description of their details, advantages and 15 differences from conventional practice, but they are thus summarized briefly herein for the reason that the system forming the subject of my present invention preferably embodies these and other features of my aforesaid system, as will be made to appear more at length in my present application, which is to be considered as in part a continuation of my aforesaid application, with respect to certain portions of the subject-matter. 20
- 25 I have, however, not only departed to a noteworthy extent from conventional usage in the provisions hereinafter set forth, but these also constitute a notable improvement over the provisions of my aforesaid application.

30 *First.*—Then, I have provided a system of coding which corresponds so closely to normal alphabetical order that the leading components of the index-numbers derived from 35 the subject-matter designations may be placed on tabs of main guide-members in association with other tabs, on the same guide-members, bearing the corresponding letters of the alphabet, so that when the installation 40 of the system is commenced, the units of matter can be, and preferably are, arranged alphabetically, in the normal manner, and the main guide-members are likewise interpolated alphabetically among the units, use being made of the guide-tabs thereon bearing 45 letters of the alphabet, for filing and finding

ABC	DEF	GHI	JKL	MNO	PQR	STU	VWY	XZ
1	2	3	4	5	6	7	8	9

- 50 If the subject-matter designation is the name of an individual, the three-digit filing-number may be coded from the first three letters of the surname; thus SMI=753; and to separate such a name as SMITH from a name such as SMILEY, a further subdivision may be made by adding a secondary filing-number, also of three digits, coded from the second three letters of the surname; thus SMILEY=753-428, while SMITH=753-730, (ciphers being added to fill out any filing-number where the surname lacks the necessary number of letters); still further

units of matter, until the latter increase to a quantity which requires subdivision of one or more of these alphabetical divisions.

55 Until such subdivision is required, the complementary index-numbers on the associated number-bearing tabs of the guides can be disregarded, nor is it necessary until then to provide the units of matter with the coded indicia, so that my novel system can be installed 60 also in existing record-files with but little need for change at the outset, merely substituting for existing alphabetical guides the novel main-guides bearing both alphabetical and complementary numerical indicia, the file- 65 record being thereby provided with the basis for infinite subdivision, by exclusively numeric guide-members, in accordance with my novel system. It is noteworthy that even though the numerical indicia be not used in 70 filing and finding matter at this stage of the system's development, nevertheless the presence of the numerical indicia, thus associated with the alphabetical indicia, has an educative effect upon the filing clerks that is of 75 value, preparatory to subsequent stages of development. This association of alphabetical and numerical indicia upon separate tabs carried by the same guide member is novel, and constitutes a notable improvement over the 80 conventional alphabetic, numeric or alphabetic-numeric-systems of indexing, and also over the system of my aforesaid application, Ser. No. 144,260.

85 *Secondly.*—As the next step in the development of the system, each unit of subject-matter in the record-file, or in that division thereof which requires subdividing, is provided with a primary filing-number comprising not less nor more than three digits, i. e., units, tens and hundreds, and these filing-numbers are derived from the subject-matter designations according to a suitable code, such as that to which reference has already been made, and which will preferably be substantially 90 as follows, viz:

subdivisions being provided for preferably by tertiary and quaternary filing-numbers derived from the first three letters of the given name and the first three letters of the middle name respectively, so that the name 110 George Stewart Smith, for example, written conventionally with its derived filing-numbers, would appear as follows:

SMI-TH-GEO-STE
7 5 3-730-3 2 5-7 7 2

115 *Thirdly.*—In order to permit easy and rapid filing and finding of the units of mat-

ter bearing these filing-numbers, to whatever extent the subdivisions may have been carried, I have provided sub-guide members having tabs bearing indicia which are preferably exclusively numerical, each sub-guide usually carrying one such tab, in a position which will cause the tab to stand in a row that has been assigned to tabs bearing one of the decimal components of one or another of

10 the index-numbers.

For the primary index-numbers there is a set of three such rows of tabs, in one of which rows stand the leading decimal components, comprising the hundreds-digits of the primary index-numbers, while in an adjacent offset row stand tabs, bearing the decimal components constituted by the tens-digits of the primary index numbers, and in the next adjacent offset row stand tabs bearing the decimal components constituted by the units-digits of the primary index numbers.

To locate the position of any unit of matter bearing a given primary filing-number, either for filing or finding the same, the user 25 will first find the guide bearing the first letter of the alphabetical designation, such as "S" in Smith, which guide carries also, on a separate tab in the hundreds row, the leading decimal component "700" of the index-number, 30 and the user will then search the adjacent row for the tens-digit component, "50", and finally will search the next adjacent row for the guide-tab bearing the units-digit component, "3", behind which guide the unit of matter will be filed or found.

To aid in identifying the guide-tabs for such operations of location, my invention provides for differentiating the guides respectively bearing components of a primary index-number, from the guides bearing components of secondary, tertiary and quaternary index-numbers, this differentiation being preferably provided for either by alignment of the three rows of tabs leading to primary 45 index-numbers, in a set separately from the set of rows of tabs leading to secondary index-numbers, and separately from those sets of rows leading to tertiary or quaternary index-numbers, where space permits, or by such 50 differentiating means as one color for all tabs in a primary series, and different colors for the secondary, tertiary and quaternary series respectively, or by combinations of differences in both alignment and color.

55 For example, the guide-tabs in a primary series may be colored blue; those in a secondary series red; those in a tertiary series yellow; and those in a quaternary series green; and the blue series and the yellow series may be aligned in the same row, while the red series and the green series may be aligned together in another row; such an arrangement having the practical value that in an operation of location the searcher will observe tabs

of a blue color first, then shift to a different 65 set of rows for observation of red tabs; and will then shift back to the first set of rows for observation of the contrasting yellow tabs; and finally shift again to observe the green tabs in contrast with the red; so that the eye 70 of the user is aided each time by the shift of alignment as well as the change of color. Where space permits of providing three or four sets of rows in separate alignment, the differentiation by color may still accompany 75 the shift of observation; or if only a single set of rows can be employed, the difference of color may serve without a shift of alignment, but it is preferable to provide for distinguishments comprising both change of color and 80 alignment.

Fourthly.—The outstanding characteristic of such a system being that it is perpetual, I have devised novel means to constitute its elements of materials which are substantially 85 indestructible by long and severe usage, by extremely varied and unfavorable atmospheric conditions, and which are non-combustible and therefore resistant to ordinary damage by fire.

It would be desirable theoretically, for the above purpose, to form all the constituent members of metal, including the units of subject-matter, such as the cards in an index and the folders containing letters, and also the 95 correspondence or other units filed, but it will be sufficient ordinarily to provide metal guide-members for such a system, as these constitute the really perpetual element of the system, as already mentioned, and are usually 100 adequate in number, and so spaced throughout the system, as to diminish the fire-risk greatly, even where they are interpolated among large numbers of combustible cards or other units of subject-matter.

Accordingly, an important object of my present invention is to provide a system of the character described, combining as elements a multiplicity of units of subject-matter, and guide-members interpolated with 110 said units, in which system certain of said elements are formed of metal.

The provision of metal members, however, in such a system, involves certain difficulties, the nature of which will now be described, 115 with the means devised to overcome said difficulties, which affect the constitution of the system in its entirety, although the difficulties and their solution may be described best in their relation to the guide-members, in the 120 first instance.

As the primary function of said guide-members, in such a system, is to afford means for filing and finding the units of subject-matter conveniently, it is essential, as already 125 indicated, to provide the guide-members with indicia related to designations on the subject-matter units, and these indicia are usually

- printed or written upon the upper margins of the conventional guides, or upon tabs formed integrally with the guides, or affixed thereto, the subject-matter units likewise 5 being preferably provided respectively with typewritten or manuscript indicia corresponding to those on the guide-members, to aid in filing the units in proper position relatively to the guide-members, as already set 10 forth, such guides and units of matter being ordinarily made of paper or paper products.

My novel three-digit index-numbers can be readily applied to the conventional guides of paper or paper-products by writing or printing 15 the three-digit numbers thereon, and in this respect possess similar capabilities and advantages as the index-numbers described and claimed in my aforesaid application, Ser. No. 144,260 wherein the indicia are exemplified as five-digit primary index-numbers. The novel three-digit index-numbers are, moreover, particularly applicable to use upon metal guides, for which they are preferable to the five-digit indicia, for the following rea- 20 sons:

In the provision of such indicia upon the upper margin or guide-members or other record-file-elements formed of metal, a difficulty arises, due to the spacial limitations of 25 said upper margin, which ordinarily varies in width from five inches, in the instance of the smaller guides, to about twelve inches, in the instance of correspondance guides, and seldom exceeds fifteen inches, in the instance of the 30 "cap" guides for legal and similar documents.

As it is desirable to have indicia of ample size, the tabs bearing the indicia should be large and not too closely crowded in their lateral rows, which are offset, for ease of observation, 40 and while the larger guide-members afford space on the upper margins for more rows of tabs than do the smaller guides, the upper margins are rarely wide enough to accommodate enough rows to receive such indicia as all 45 the letters of the alphabet, or numbers, in very extended series, even upon the larger members, and it is therefore desirable to devise an arrangement of tabs suited to the spacial limitations of the smaller members, in order 50 to preserve the convenience, in operations of location, afforded by an arrangement of indicia which is substantially uniform throughout the different sizes of members.

Such uniformity is desirable also in order 55 to reduce to a minimum the operations to be performed in applying the indicia to the metal guide-members, for it is difficult to provide metal guides, or other metal members, with sufficiently permanent indicia by a single 60 operation of printing the indicia upon the metal in the conventional manner of printing such indicia upon a guide of paper or paste-board; and it is equally difficult to provide legible and permanent indicia in the form of

typewritten or manuscript characters upon 65 such metal guides.

The most satisfactory method of providing the metal guide-members with permanent indicia is to treat the metal by means of dies, in order to emboss the alphabetical or numerical indicia in relief or intaglio characters in the metal, or to enamel or etch the surface thereof, in order to secure a marking as permanent as the perpetual character of the system requires, but such treatment may be too expensive when 70 providing for very extended numbers running up into millions, (if numerical indicia are applied in the five-digit form shown in my aforesaid application,) by reason of the prohibitive cost of initial construction, and the constant 75 maintenance, of the very large set of dies which would be required to apply these very extended indicia to metal guide-members in such a permanent manner as to render the 80 system perpetual.

Accordingly, I have overcome, the above difficulty due to spacial limitations, and the further economic difficulty of forming numerical indicia in extended series with a large 85 number of dies, by my present novel arrangement of three-digit index-numbers, which is suited to all sizes of file-record elements, whether or not formed of metal, and is suited especially to guide-members formed of metal, such as aluminum, and this constitutes an im- 90 portant feature of my present invention, as the three-digit indicia coded and arranged according to my novel system above described can be applied universally to every metal 95 guide-member of such a system by the use of 100 a relatively small number of dies.

In effecting this objective of my invention, I provide blanks of sheet metal of any desired or suitable form, such as the conventional shapes and sizes of guide-members used in existing files, preferably using those sizes which have been adopted as standard, to permit the ready adoption of my improvements in existing files, and I proceed to apply to these blanks the basic components of the indicia, preferably by embossing the same along the upper 105 margin of each blank.

My invention makes it possible to provide all the stock guides required for a perpetual and infinitely expandible system, by the use 110 of less than ten different sets of blanks, and, therefore, less than ten different dies to form the blanks, inasmuch as I have devised my novel combination of alphabetical and numerical indicia for the guides, already described, with special reference to the formation of the numeric indicia upon the margins of the blanks in the same operation by which the complementary alphabetic indicia are embossed thereon; and I have so devised 115 my novel code already described, as to permit the formation of several letters of the alphabet on each blank, by the same emboss- 120 125

ing operation with several decimal components of the numerical indicia; and I have so devised the organization of the decimal components in offset rows as to permit the formation on each blank of several sets of decimal components of the numerical indicia, concurrently with the formation thereon of the letters of the alphabet assigned to that blank; the result, and carefully planned purpose, of this thorough organization of index components in a systematic arrangement, being to permit the production with maximum economy of every guide which users may require, in any desired quantity, and with the utmost 15 expedition.

A further object achieved is to permit the manufacturer of the guides to carry as stock only the unembossed metal blanks, of standard sizes, inasmuch as the embossing operation may be performed thereon so expeditiously, in response to requests for those main-guides carrying the letters of the alphabet for which the demand may predominate at any given time, that the demand can be met readily without forecasting the same, and as the exclusively numerical sub-guides can be used with any main-guides, the manufacturer can meet the demand for sub-guides with equal expedition, in the desired quantities, and as a corollary the user need only stock such quantities as will provide a conservative margin over the guides in current use.

The foregoing improvements unite to yield a filing system of a perpetual character, infinitely expandible, and in which the perpetual elements are of an indestructible character, so that the system is not subject to wasteful replacements, and accordingly the supplies are vested with a staple character that permits a stabilization of prices, and an accuracy of estimation in cost of installation and maintenance, which is beneficial alike to user and producer, and which the art has lacked heretofore.

The various features of my invention will be illustrated and described fully in the accompanying drawings and specification and pointed out in the claims.

50 In the drawings,

Figure 1 is a view in perspective of an assembly of subject-matter-cards or units with interpolated guides or members, constituting a record-file in the formation of which my improvements have been embodied.

Fig. 2 is a similar view of a portion of the record-file shown in Fig. 1, after expansion thereof by the addition of numerous subject-matter-units, and subdivided by the interpolation of sub-guides required for convenience in filing and finding the subject-matter-units, in accordance with my novel system.

Fig. 3 is a similar view of a portion of the record-file shown in Figs. 1 and 2, after expansion in still greater detail by the addition

of very numerous subject-matter-units, and subdivided further by an appropriate quantity of sub-guides, within a single alphabetical division of the record-file.

Fig. 4 is a face view of an instruction card 70 setting forth the code for my improved perpetual guide-system.

Figure 5 shows in perspective, on a larger scale, nine blanks which represent in the aggregate the entire series of blanks from 75 which a complete equipment of guides for such a record-file can be formed, according to my system.

Fig. 6 is a face view on a smaller scale of a modified blank, being one of a series of 80 nine, such as those shown in Fig. 5, but much larger.

Fig. 7 is a detail view in perspective of a fragment of one of the blanks shown in Fig. 5, after its formation into a guide by "tabbing" or cutting away the upper margin thereof at all regions except the regions of the particular letter and decimal component to be designated by the guide, and this figure shows the inclined arrangement of the upper 90 margin, for convenience in observation by the user.

Fig. 8 is a face view of a card constituting one of the subject-matter-units of the record-file illustrated, and isolated therefrom, to 95 show more clearly the subject-matter designation on the card, and the filing-numbers coded from, and related to, the subject-matter designation.

In the embodiment of my invention selected 100 for illustration and description to permit ready and complete understanding of my improvements, a record-file is shown in different stages of its development, the record-file comprising as one element a multiplicity 105 of conventional index cards distinguished in general by the reference character *a*, throughout the drawings, unless specifically distinguished otherwise, and these cards carry upon their faces such subject-matter as the 110 record-file is designed to include; as for example the names, addresses and business of persons, firms and corporations, one of these cards being shown in detail, isolated, in Fig. 8.

115 The cards *a* thus constitute subject-matter-units, and are so referred to generically herein, whatever may be the nature of the subject-matter they carry, and this term "subject-matter-units", or, more briefly, "units of matter", applies not only to index cards, but to all other articles subject to filing, such as letters, folders for correspondence, and objects of the nature of photographs, catalogs, etc., the kind of units being unimportant, as 120 well as their material, form, size, color and other physical characteristics.

To permit easy identification of the respective units of matter, each unit *a* is provided, preferably, with an individual designation 130

of its subject-matter, such as the name "George Stewart Smith" upon one card, as shown at *a**, the name occupying the conventional place for such designations, viz, the 5 upper left-hand corner of the card, with the surname written first; then the "given" name and the middle name, in the order mentioned.

Thus far, the procedure described follows conventional practice so closely as to render 10 the installation of my improved system easy even for persons having only a very elementary knowledge of the art of filing, inasmuch as the cards *a*, or other units of subject-matter, can be readily assembled in alphabetical 15 order, or approximately alphabetical order, either with or without the guide-members shown in the drawings, these guides being distinguished in general, throughout the drawings, by the reference characters *b*, and 20 constituting in the aggregate another element of the record-file, and one which is designed to be perpetual, in accordance with the invention forming the subject of generic claims in my copending application for United States 25 Letters Patent, Ser. No. 144,260, as already noted hereinbefore.

The guides *b* may be of any material, shape and size suitable to carry my invention into effect, and may be provided with any indicia 30 suitable for that purpose.

Preferably they will be of standard sizes and shapes, and in accordance with an important object of my invention the guides are 35 preferably formed of a material indestructible by long and severe wear, not affected by unfavorable atmospheric conditions, and not combustible. For this purpose metal constitutes the best material, and aluminum is preferred, by reason of its light weight, its bright 40 and attractive appearance in the file, which it aids to illuminate, by reflection of light; and by reason of its agreeable "feel" when handled frequently, and other qualities characteristic of aluminum, and which need not 45 be detailed herein, except that its use as a material for guides introduces a permanent series of fire-proof partitions in the file, greatly diminishing the hazard of complete or partial destruction by fire of the units of 50 matter when the latter are formed of conventional material, such as paper or paper products; and the fire hazard may be further reduced by extending the use of aluminum as a material for other elements of the record 55 file, so far as found convenient and desirable.

As the principal function of the guides *b* is to aid in the location of any desired unit of matter, for reference, filing and finding, each guide is provided with indicia related to 60 the subject-matter designations upon the units of matter *a*, according to the system disclosed and claimed in my aforesaid application Ser. No. 144,260, with certain important improvements which have been already indicated in part, and which will appear more

clearly from the following detailed description of the record-file and of the different stages of its development.

Initial stage of development.

According to the aforesaid system, and the first-mentioned of my present improvements thereon, the guides *b* comprise a series of main guides provided with correlated alphabetical and numerical indicia, the series being shown complete in Fig. 1, which represents the record-file in the initial stage of its development, each main-guide *b* of this series having thereon a tab *b*¹ which bears a letter of the alphabet, and a separate tab *b*² which bears the leading decimal component of an index-number, or index-numbers, derived from the subject-matter designations *a** upon the units of matter *a*, according to a suitable code, which is preferably the code already set forth.

By this novel association of alphabetic indicia with numerical indicia, I secure the advantages of alphabetic indexing at the stage of original installation, as the guide-tab *b*¹ with the letter "A", for example, leads directly to all units of subject-matter whose designations, arranged conventionally, begin with the letter "A", and these units may be filed and found most expeditiously by a simple operation of locating the desired unit among those units standing between the "A" and "B" tabs borne by the main-guides; and so on throughout the alphabet, the filing clerk not being required to pay attention to the complementary separate tabs *b*² of the main guides, bearing the leading decimal components of the numerical indicia.

Such indexing designedly follows conventional usage, by preference, and as such, does not require particular description, in general, but special attention is directed to the novel organization of the letter-bearing tabs *b*¹ in their relation to the tabs *b*² bearing the leading decimal components of the numerical indicia, which organization is preferably substantially that illustrated throughout the drawings, and most clearly shown in Fig. 1.

Where use is made of my novel code, the main-guides *b* having tabs *b*¹ bearing respectively the letters A, B and C are each provided preferably with a separate tab *b*² bearing the leading decimal component "100" of what may be termed the "primary index-number" of the numerical indicia, the term "primary" being used without technical limitation, but for the sake of brevity, to designate the initial step in the unlimited subdivision of which my system is capable, while the terms "secondary", "tertiary" and "quaternary" index-numbers, are likewise merely conveniently brief ordinal expressions to identify successive further stages of subdivision accompanying the progressive expansion of the subject-matter and the attendant inter-

polation of the requisite numerical sub-guides.

So also, the main-guides b having tabs b^1 bearing respectively the letters D, E and F are each provided preferably with a separate tab b^2 bearing the leading decimal component "200" of another "primary" index number of the numerical indicia; while the main guides b having tabs b^1 bearing respectively the letters G, H and I, are each provided preferably with a separate tab b^2 bearing the leading decimal component, "300" of still another "primary" index number; and so on, through the nine groups of letters among which the letters of the alphabet are divided in accordance with the system of coding which I have illustrated.

For the sake of convenience in observation I prefer to place the letters of the alphabet upon tabs b^1 situated toward the left-hand side of the upper margins of the main guides, in a plurality of rows offset from left to right, so that the tabs b^1 bearing the letters A, D, G, J, M, and so on, are in a row occupying preferably the first position at the left, while the letters B, E, H, K, and so on, are in the next offset row, and the letters C, F, I, L, and so on, are in a third offset row or position; the leading decimal components of the primary index-numbers being aligned in a single row of tabs b^2 which constitutes the first indexing position of the numerical indicia, not far removed from the third row of alphabetical indicia.

The record-file in its initial stage presents substantially the appearance illustrated in Fig. 1, and is operable as an alphabetically indexed system, with the subject-matter units a not requiring index-numbers, and the guide-tabs b^1 displaying the index-letters in relatively compact, but visibly extended position.

To promote visibility, I prefer to form the letters and numerical indicia in bold relief or intaglio characters upon the tabs b^1 and b^2 respectively, as illustrated in detail in Fig. 7, at c and c^1 , and when, as I prefer, these tabs are constituted as integral extensions of an aluminum guide, I prefer to enamel the face d of the tabs, surrounding the letter or number, and I leave the embossed portion free from color, in the naturally bright color of the aluminum, which is in attractive contrast with the enamel, of whatever color, my preference as a color for the tabs b^1 bearing the letters of the alphabet, and the tabs b^2 , bearing the decimal components of primary index-numbers, being blue, this indicating the first three letters of the surname. This color blue is indicated conventionally throughout the drawings by a hatching of horizontal lines, and in Fig. 1 all of the tabs shown are indicated as blue in color.

I prefer also to incline the tabs b^1 and b^2 rearward, as indicated in the drawings, this inclined position being impossible to obtain

permanently by bending back the tabs of conventional units of paper or paper products, and being only effected by separate attachments, heretofore, so that my integral structure of aluminum guide has made possible this highly desirable arrangement of a permanently inclined guide-tab constituted as part of the guide itself.

I do not limit myself, however, to the use of indicia upon integral tabs, but contemplate their use upon attachments for the guides, such for example as those forming the subject-matter of my copending application for United States Letters Patent, Ser. No. 589,319, filed Sept. 20, 1922.

80

Second stage of development.

When the quantity of subject-matter units a has increased to such an extent that alphabetical indexing is no longer convenient, and it is desired to subdivide one or more of the groups, theretofore indexed by letters of the alphabet, such as the subject-matter units a indexed by the main guide b bearing the letter "S", these latter subject-matter units a are first respectively provided preferably with filing-numbers coded from their subject-matter designations in the manner already indicated, and as shown at a^1 upon one of the subject-matter units a which constitute that portion of the expanded record-file illustrated in Fig. 2, including the units indexed by the letters Q to XZ, the units from B to P inclusive being omitted to save space in this figure of the drawing, their absence being indicated by the gap between the main "A" guide and the main "Q" guide.

For example, the unit a bearing the designation "Smith, George Stewart" at a^1 in Fig. 2, is shown partly withdrawn to exhibit the primary filing-number which has been applied thereto, as illustrated at a^1 , being the number 753, which is derived from the first three letters of the surname according to the code hereinbefore set forth, and which code is preferably displayed upon an instruction card furnished to users with the original installment of record-file elements, such an instruction card being shown in Fig. 4, to which reference may be made advantageously to aid in understanding the present description of the various stages of development of the system.

This primary filing-number, and the letters from which it is coded may, and preferably will, be typewritten upon the unit a in juxtaposition, viz, SMI 753 and for this purpose use may conveniently be made of the typewriting device shown and described in my aforesaid application, Ser. No. 144,260, or of any similar device suitable for the purpose of providing the alphabetical and numerical indicia concurrently, for the sake of accuracy and speed.

125

130

Each subject-matter unit a in that portion of the file-record which is to be subdivided, is so provided with a primary filing number a^1 thus consisting of no more and no less than 6 three digits, and coded in the same manner from the first three letters of the surname forming part of the conventional subject-matter designation a^* on each of the said units of matter in the portion of the record-file shown in Fig. 2. These three-digit numbers a^1 will be found quite sufficient to differentiate the units of subject-matter within the "S" division at this stage of development of the system, in connection with the sub-guides 10 now to be described.

Reverting again to the unit of matter bearing the designation George Stewart Smith, it has been seen that whether in the earlier stage of development of the record-file shown in 20 Fig. 1, or in the stage now being described, shown in Fig. 2, the above unit stands back of the main guide b which bears on its tab b^1 , the alphabetical index letter "S" and bears upon a separate tab b^2 the number "700" 25 which has been defined as the leading decimal component of the primary index-number, so that it constitutes the first guide to be consulted in filing or finding the subject-matter unit bearing the designation George Stewart 30 Smith, or any other unit whose designation, written conventionally, begins with the letters SMI, or written as above 35 $\begin{smallmatrix} \text{SMI} \\ 753 \end{smallmatrix}$, the filing number a^1 being read "Seven hundred and fifty three" rather than "Seven five three" so that the leading component "Seven hundred" suggests its numerical equivalent "700", on the tab b^2 of the main "S" guide b .

Following the above mode of description, 40 the next decimal component of the primary filing number is that of the tens-digit, which is "50" in the present instance, and in accordance with my invention, provision is made of a sub-guide b^3 having a tab b^4 bearing the decimal component "50" in a position offset, toward the right hand preferably, from the position in which stand the tabs b^2 bearing the hundreds-digits, or leading, components of the index numbers, the number "50" appearing 45 therefore in a row assigned to the tabs b^4 of all the tens-digits components, as shown in Fig. 2, and other figures, where will be found for example, tabs b^4 bearing the numbers "10", "20", "30", "40", ahead of the tab b^4 bearing the number "50", so that starting with the number "700" on the tab b^2 of the main "S" guide b , and shifting to the tens-digit row of tabs b^4 , the searcher runs quickly 55 over the "10", the "20", the "30", and the "40" 60 until he arrives at the "50", behind which he finds the unit or units of matter bearing the filing-number "753", that is to say, every unit whose subject-matter designation begins with the letters SMI, and among these will be the 65 George Stewart Smith unit, which can be

found readily in the instance shown in Fig. 2 for the reason that the record-file does not happen to contain an extremely large number of cards or units bearing designations beginning with SMI, so that it is sufficient to index 70 the numbers "753" by the hundreds-guide "700" and the tens-guide "50", without adding a units-digit guide "3".

Such a guide may be added whenever required, however, and, in accordance with my invention, the sub-guides b^5 bearing the units-digits components of the primary index numbers will have tabs b^6 in a position forming a row, offset from, and next adjacent to, the above described row of tabs b^4 bearing 80 tens-digits components, such a row of units-digits components appearing in Fig. 2, with the units-digit "4" upon a tab b^6 which appears in this adjoining row as the next tab to the b^4 tab "10" following the "S" "700", so that all subject-matter units in the "S" "700" 85 division bearing primary filing numbers between 700 and 714 would be filed and found between the "10" tab b^4 and the "4" tab b^6 in that division.

Similarly, as the next tab in the units-digits row b^6 bears the number "6", all subject-matter-units bearing the primary filing-numbers 714 and 715, in this division led by the "S" "700" main-guide, will be filed and found 90 between the units-digit sub-guides "4" and "6"; while all subject-matter units bearing primary filing numbers from 716 to 719 inclusive will be filed and found between the tab b^6 of the aforesaid units-digit sub-guide 100 b^6 bearing the decimal component "6" and the next sub-guide b^8 whose tab b^4 bears the decimal component "20", in the tens-digit row, there being no units-digit sub-guides for filing numbers from 717 to 719 for the reason 105 that there are relatively few subject-matter units bearing those filing numbers, and therefore they can be readily found and filed as above described.

So also there are no sub-guides in the units-digit row b^6 for "S" numbers running from 721 to 799, with the exception of the sub-guide "5" between the tens-digit sub-guides "20" and "30", and the sub-guide "7" between the tens-digit sub-guides "50" and "60", inasmuch as the subject-matter units bearing numbers from 721 to 799 are sufficiently indexed, generally speaking, for convenient reference, filing and finding, by the tabs b^4 of the tens-digit sub-guides b^8 bearing the 110 decimal components "20", "30", "40", etc.

What has been said above in describing the sub-division of subject-matter units back of the main-guide "S" "700" in this second stage of development of the system, applies equally to the subdivision of subject-matter units in the other alphabetical divisions, and it may be noted that the subject-matter units back of the main-guide "Q" "600", and those back of the main-guide "Y" "800" and those back 125 130

of the main-guide "XZ" "900", have not increased in number sufficiently to require even subdivision by the interpolation of tens-digit guides, while other alphabetical divisions 5 have been more or less divided, as indicated, in accordance with the requirements of convenience in reference.

Third stage of development.

- 10 When the quantity of subject-matter units a has increased further to such an extent that the primary index-numbers composed as above described of three digits, read in continuity from row to row upon the set of rows 70
15 in which are aligned respectively the tabs b^2 , b^4 and b^8 bearing the leading, or hundreds, decimal components, the tens decimal components and the unit-digit decimal components, no longer afford a sufficiently convenient means of indexing the subject-matter units in any alphabetical division, and it is desired to effect a further differentiation between the subject-matter units which have 75
20 been subdivided already by the primary sub-
25 guides as above described, my invention provides for such further subdivision as follows:
Preferably the subject-matter units a in the alphabetical division or divisions, or in such subdivisions thereof as are to be further 80
30 subdivided, as for example the subject-matter units back of the primary main-guide "S" "700", (which units of matter are illustrated in Fig. 3 as having increased in quantity to such an extent that they occupy more space 85
35 in the file than did the original quantity of subject-matter units a shown in all the alphabetical divisions of Fig. 1), are now provided respectively with secondary filing numbers, a^2 , coded from their subject-matter designations in the manner already described with 90
40 reference to the primary filing numbers, but derived from the second three letters of the surnames.

Accordingly, when so provided with a 45 secondary three-digit filing number, in addition to the primary three-digit filing number already thereon, the filing indicia upon the George Stewart Smith subject-matter unit a , as shown in Fig. 3, would exhibit the primary 50 and secondary filing numbers, a^1 , a^2 , written in juxtaposition with the name Smith, as follows:

SMI-TH.
753-730

55 The secondary filing number is 730, being provided with the final cipher for the reason that the name Smith only has five letters, and as I prefer to adhere strictly to the three-digit 60 arrangement of the filing numbers, principally for the sake of rapid and accurate observation, as well as to aid the memory and to facilitate the formation upon the guides of the decimal components of all such index 65 numbers as may be required for convenience

in operations of location, to whatever extent the subdivisions may be carried, it is to be understood that wherever letters are lacking in a surname, or in any other portion of a subject-matter designation, to furnish the 70 basis for a complete three-digit filing number, the necessary cipher or ciphers will be added to fill out the filing number, whether the latter be a primary, secondary, tertiary, quaternary or other filing number, for my invention contemplates subdivision to an extent only governed by convenience in operations of location, and which may be carried to an unlimited degree. 75

For the sake of compactness in illustration, and brevity in description, I have shown in Fig. 3 a portion of a record-file which has been expanded by addition of subject-matter units in the alphabetical division back of the main-guide "S" "700" to an extent which requires in certain places primary, secondary, tertiary and quaternary guides to permit convenient location of the respective subject-matter units a , and I will so describe this portion of the filing record, inasmuch as it not 80 seldom happens that the growth or expansion of such a system is so rapid, or the quantity of subject-matter units is so great at the time of installation, that the sub-division 85 must be made at one time which ordinarily 90 would occur in successive stages distributed over considerable periods, it being understood that the development of the system by such stages comes equally within the purview 95 of my invention. 100

What I may term the "tertiary" subdivision of the subject-matter units proceeds in exactly the same manner as did the primary division thereof already described in detail, so far as the basic principle is concerned, and so does the "quaternary" subdivision, and so may any subsequent subdivision, as a general rule, the derivation of the filing numbers from the subject-matter designations being capable of such variations as 105 110 may be desired and found suitable.

For purposes of a "name-filing" record-file such as that selected for illustration, the tertiary filing numbers a^3 may be coded from the first three letters of the given name, and the quaternary filing numbers a^4 may be coded from the first three letters of the middle name, where such exist, in each instance, so that in the instance of the George Stewart Smith unit, the complete series of filing numbers, coded as above, and written in juxtaposition with corresponding letters of the name, stands as follows, and so appears upon the unit as shown in Fig. 8, viz., 115 120 125

SMI-TH.-GEO-STE
753-730-325-772

The card constituting the above George Stewart Smith unit of subject-matter is shown also at the extreme rear of that por- 130

tion of the record-file illustrated in Fig. 3, and a description of the guides by which it is indexed will serve as the simplest mode of rendering clear the constitution of the file at this stage in the development of my novel system.

In the operation of locating the George Stewart Smith card, the filing clerk would first ascertain the position of the main-guide 10 "S" "700", then find the sub-guide b^3 bearing the tens-digit decimal component "50" of the primary index-number, which is shown in Fig. 3 as standing at the head of that portion of the file which is illustrated, 15 for the sake of convenience in description, the gap between it and the "S" "700" main-guide being left to indicate that there may be intervening subject-matter units with interpolated guides, not shown.

20 Then the clerk finds the sub-guide b^5 having a tab b^6 with the units-digit "3", in the row appropriate thereto, which is the third row of the first set of three rows of exclusively numerical decimal components of the three-digit index-numbers shown in Fig. 3, constituting the primary series of guide-tabs indexing the primary filing number "753"; the next step in the operation of location being to search for the leading component of the 25 secondary index-number "730" which will be found in the next adjacent row of tabs, b^8 toward the right, as a hundreds-digit "700", the guide upon which it is formed being further distinguished by the reference 30 character b^7 for convenience in description.

The tabs bearing decimal components of the secondary index-numbers are colored differently from those bearing decimal components of the primary index-numbers, and 40 in Fig. 3 the tab b^8 is illustrated as of red color, indicated by vertical hatching, as are all the tabs bearing secondary decimal components, and being thus distinguished clearly from the blue tabs in the set of rows bearing 45 the primary decimal components, the clerk is aided both by the difference of color, and by the shift of observation to another row, or set of rows, to locate readily not only the leading decimal component "700" 50 of the secondary number, but also the tens-digit component "30", carried by a tab b^{10} , upon a sub-guide b^9 , in Fig. 3, the location of which is all that is necessary to complete the search for the secondary index-number 55 "730", there being no units-digit other than the cipher which stands in place of the missing sixth letter of the name Smith.

I have shown, however, several sub-guides 60 b^{11} bearing secondary units-digit components, upon tabs b^{12} at the extreme right-hand position in Fig. 3, and of these tabs, the first, or nearest to the front, bearing the units-digit decimal component "2", is read with the leading decimal component "400" and the 65 tens digit decimal component "40", in preced-

ing rows, constituting the set appropriate to secondary index numbers, so that thus read from left to right in continuity they constitute the secondary index-number "442", and all subject-matter units in this sub-division 70 having subject-matter designations in which the second three letters of the surname are to be coded "442" will be filed and found back of the sub-guide b^{11} bearing the secondary index tab "2", next to the rear of the 75 tens digit-guide "40" which follows next after the leading secondary hundreds decimal component "400".

Reverting to the search for the George Stewart Smith location, the next operation 80 will be to find the tertiary index-number "325" which has been coded from the first three letters "GEO" of the given name "George", as above described, and accordingly the clerk searches for tertiary tabs respectively bearing a hundreds-digit component "300", a tens-digit decimal component "20" and a units-digit decimal component "5", these tabs of tertiary guides being distinguished in Fig. 3 by the reference characters b^{14} , b^{15} and b^{16} 85 respectively, and the body portions of the guides being distinguished by the reference character b^{13} , in general. The leading decimal components of the tertiary series are shown in Fig. 3 as occupying positions in the 90 same row as are the leading decimal components of the primary series, i. e., the first row following the rows of alphabetical indicia, so that the tertiary tabs are given a contrasting color-yellow,—(indicated by cross-hatching) 95 which distinguishes them clearly from the blue primary tabs, while the shift in observation from the extreme right hand row of the secondary series with its red tabs, to the extreme left-hand row of yellow numerical indicia further aids the eye of the clerk in 100 searching for the tertiary number "325", the latter being found in Fig. 3 toward the rear of the file.

The operation of location still requires a 110 search for the quaternary index-number "772", this three-digit index-number being coded from the first three letters "STE", of the middle name "Stewart", as are all quaternary index-numbers, preferably, the quaternary sub-guides b^{17} having tabs b^{18} , colored green, as indicated by diagonal hatching in Fig. 3, and, without further detailed description, in view of the complete description heretofore given with reference to the primary, 115 secondary, and tertiary index-numbers, it will suffice to note that the quaternary index-number "772" is indexed simply by a quaternary sub-guide b^{17} , having a green tab b^{18} at the rear of Fig. 3, bearing the hundreds-digit 120 decimal component "700" of the quaternary index-number, no further sub-guides being necessary for final location of the George Stewart Smith unit, which stands closely back of the above "700" guide, there being 125 130

few, if any, units of matter having the same combination of primary, secondary, tertiary and quaternary index-numbers as those associated with the name George Stewart Smith.

It will be observed, however, that the very absence of sub-guides back of the quaternary sub-guide "700" indicates possibilities of further subdivision by the use of the exclusively numerical sub-guides of the quaternary series in the tens-digit position or row and the units-digit row respectively. The tabs b^{18} are colored green preferably, in contrast to the red tabs b^{10} of the secondary series, which occupy the same rows in the form of file illustrated in Fig. 3, but it is to be understood that the combination of colors illustrated is optional, and the presence of more than one series of index-numbers in any set of rows is not necessary, nor is it necessary to have plural sets of rows, if convenience of observation can be served in particular instances by the alignment of all the hundreds decimal components, whether of primary, secondary, tertiary or quaternary index-numbers, in a single row, the tens-digit decimal components in a second row and the units-digit decimal components in a third row, but ordinarily the presence of more than two different series, such as the primary and tertiary components, in a single row, renders them crowded and not convenient to observe.

The mode of operation of my improved system is clearly apparent from the above description, and it is considered unnecessary to describe an extended series of searches, as the organization of the system is such as to bring it within the usual scope of operations of clerks skilled in the art of filing, but as one further illustration of the manner in which units of matter are located in different positions within the file, I have shown at a^5 in Fig. 3 the card or subject-matter unit of one Benjamin A. Smith, partly withdrawn to show his name written conventionally as a subject-matter designation, and also the appropriate primary, secondary and tertiary filing-numbers in juxtaposition with the portions of the subject-matter designation from which they have been derived, viz.,

SMI-TH.-BEN
7 5 3-73 0-1 2 5

It will be seen readily by what guides this name is indexed, and that the provision of a tertiary filing-number is amply sufficient to differentiate it from the George Stewart Smith unit for convenient location in reference filing and finding.

It may be noted that the employment of ciphers to fill out filing-numbers where the subject-matter designations lack the appropriate number of letters, has as a corollary that there are no filing-numbers from 101 to

109 and 201 to 209, etc. Furthermore there is no filing number less than 100, when strict adherence is had to the three-digit formation of index-numbers, as I prefer.

I have already noted that the novel combination of alphabetical indicia with complementary, exclusively numerical indicia, formed upon separate tabs integral with the same guide-member, and the organization thereon of the several series of three-digit index-numbers with their decimal components displayed in sets of three adjacent rows on successive guides, is the result of a carefully planned purpose to make it possible to provide all the stock guides required for a perpetual and infinitely expandible system, by the use of less than ten different dies to emboss a corresponding number of blanks, for the concurrent formation on each blank of several sets of decimal components of the numerical indicia, and several letters of the alphabet, thereby to permit the production with great expedition and maximum economy of every guide which users may demand, in any desired quantity.

For this purpose, any suitable blanks may be used, and I have illustrated in Fig. 5 nine blanks which represent in the aggregate the entire series of blanks from which a complete equipment of guides for such a record-file can be formed, according to my novel system, in such quantities as they may be required, from time to time, and without the need for ascertaining or forecasting probable future requirements, this novel set of blanks constituting an important feature of my invention.

The blanks shown in Fig. 5 are preferably uniform in shape and size, and suitably designed to be utilized in the production of main-guides and sub-guides of the type illustrated in various figures of the drawings, and distinguished by the reference characters, b , etc.

These blanks are distinguished by the reference characters B^1 — B^9 inclusive, and each blank bears, toward the right-hand side of its upper margin, duplicate sets of embossed numbers, displayed in different indexing positions, and, toward the left-hand side of the upper margin, each blank bears embossed letters of the alphabet, in different indexing positions, three letters for each blank, Fig. 5 indicating, in rather diagrammatic form, the arrangement of letters and numbers upon the respective blanks B^1 — B^9 , which are so clearly illustrated as not to require special description, it being understood that guides are produced from the appropriate blank by the conventional operation of "tabbing off."

For example, the blank B^1 bears on its upper margin the following indicia, viz.,

A B C 100 10 1 100 10 1; and the blank B^2 bears D E F 200 20 2 200 20 2;

and so on throughout the series of nine blanks, so that to form a complete set of main-guides, capable of serving as the alphabetical indicia for any size of record-file, and also furnishing the basis for infinite sub-division by exclusively numerical indicia, the manufacturer need only emboss three blanks like B^1 , and three each like B^3 — B^8 inclusive, with one like B^0 , making twenty-five in all, after which he will "tab-off" the blanks to produce the main-guides shown in Fig. 1.

Thus the "A" "100" main-guide shown in Figs. 1, 2 and 7, is produced by embossing a blank like B^1 and tabbing or cutting away the "B" and "C" and all the decimal components other than the "100" next to the "A"; the "B" "100" main-guide is produced by embossing another blank like B^1 , and cutting away the "A" and "C" and all the decimal components other than the "100" next to the "B" and the "C" "100" main-guide is produced by embossing a third blank like B^1 , and cutting away the "A" and "B" and all the decimal components other than the "100" next to the "C".

The "D" "200", "E" "200" and "F" "200" main-guides are similarly produced from three blanks like B^2 ; and so on until the single "XZ" "900" main-guide has been formed from a blank like B^0 .

The formation of a sub-guide having a tab bearing any decimal component in any indexing position whatever of those provided for, may be accomplished by cutting away from the margin all other decimal components and the letters, leaving only a "50" or a "3" or any other desired decimal component, in the proper indexing position.

The tabs thus left integral with the main-guides are then preferably bent over to present the indicia in a position permanently inclined rearwardly and upwardly relatively to the face of the guides, as shown in detail in Fig. 7, to promote ease of observation, and when it is desired to provide for subdivision of the subject-matter units beyond that accomplished by the use of primary three-digit filing-numbers, I regard it as very desirable to enamel or otherwise color the tabs distinctively according to the series in which they are to be used, say blue for primary guides, red for secondary, yellow for tertiary and green for quaternary, as hereinbefore set forth, this being a suitable stage of their manufacture at which to supply such a differentiating characteristic or distinction. This color scheme is referred to in the instruction card shown in Fig. 4.

In Fig. 7 I have shown in perspective a fragmentary view in detail of one corner of the main-guide "A" "100", which shows clearly the embossed indicia, with the enamel applied at d to form a blue field of color on the tabs b^1 and b^2 contrasting with the enclosed

face of the indicia, the latter being preferably left in the bright natural color of the aluminum.

This figure also illustrates clearly the inclined position of the integral tabs b^1 and b^2 .

In Fig. 6, I have shown a blank B^{10} of larger proportions than those illustrated in Fig. 5, and in which advantage is taken of the additional space on the upper margin to provide for three sets of decimal components, so that the primary, secondary and tertiary index-numbers may each have separate sets of rows for their decimal components, it being understood that this blank B^{10} is one of a series of nine like those shown in Fig. 5, from which can be formed all guides of an equipment of this size, which is the standard correspondence size; a similar set of blanks may be provided for an equipment of legal size guides, etc.

Having illustrated and described my invention thus fully, and suitable means by which the same may be carried into effect, I wish it to be understood that I do not limit myself to the specific materials and embodiment selected for illustration and description, by way of example, nor in general do I limit myself otherwise than as set forth in the claims, read in connection with this specification.

What I claim as new, and desire to secure by Letters Patent, is:

1. A system of guides for indexing record-files of the class having subject-matter units provided with subject-matter designations; said guide-system being characterized by main-guides each respectively displaying a letter of the alphabet in an indexing position and displaying respectively, in a separate indexing position, a numerical index coded from said alphabetical index to the subject-matter designations.

2. A system of guides for indexing record-files of the class having subject-matter units provided with subject-matter designations; said guide-system being characterized by main-guides each respectively displaying a letter of the alphabet upon a tab in an indexing position and displaying respectively, upon a tab in a separate indexing position, a numerical index.

3. A system of guides for indexing record-files of the class having subject-matter units provided with subject-matter designations; said guide-system being characterized by main-guides each respectively displaying a letter of the alphabet in an indexing position and displaying respectively, in a separate indexing position, a complementary numerical index.

4. A system of guides for indexing record-files of the class having subject-matter units provided with subject-matter designations; said guide-system being characterized

5 by main-guides each respectively displaying a letter of the alphabet in an indexing position and displaying respectively, in a separate indexing position, an exclusively numerical index.

6 5. A system of guides for indexing record-files of the class having subject-matter units provided with subject-matter designations; said guide-system being characterized by

10 main-guides each respectively displaying a letter of the alphabet in an indexing position and displaying respectively, in a separate indexing position, a leading decimal component of a set of numerical indicia related to

15 said subject matter designations.

6 6. A system of guides for indexing record-files of the class having subject-matter units provided with subject-matter designations; said guide-system being characterized by

20 main-guides each respectively displaying a letter of the alphabet in an indexing position and displaying respectively, in a separate indexing position, a leading decimal component of a set of numerical indicia related to said

25 subject matter designations, and sub-guides displaying respectively succeeding decimal components of said numerical indicia.

6 7. A system of guides for indexing record-files of the class having subject-matter units 30 provided with subject-matter designations; said guide-system being characterized by main-guides each respectively displaying a letter of the alphabet in an indexing position and displaying respectively, in a separate indexing position, the leading decimal component of an index-number coded from said alphabetical index to the subject-matter designations.

6 8. A system of guides for indexing record-files of the class having subject-matter units 40 provided with subject-matter designations; said guide-system being characterized by main-guides each respectively displaying a letter of the alphabet in an indexing position and displaying respectively, in a separate indexing position, the leading decimal component of a three-digit index-number coded from said alphabetical index to the subject-matter designations.

6 9. A system of guides for indexing record-files of the class having subject-matter units 50 provided with subject-matter designations; said guide-system comprising main-guides respectively characterized by a plurality of integral tabs, one of said tabs displaying a letter of the alphabet in an indexing position, and another of said tabs displaying, in a separate indexing position, the leading decimal component of a set of numerical indicia

60 related to said subject matter designations.

10. A system of guides for indexing record-files of the class having subject-matter units provided with subject-matter designations; said guide-system being characterized by

main-guides each respectively displaying a letter of the alphabet in an indexing position and displaying respectively, in a separate indexing position, the leading decimal component of a three-digit index-number coded from said alphabetical index to the subject-matter designations, and sub-guides displaying respectively succeeding decimal components of said index-number.

11. A system of guides for indexing record-files of the class having subject-matter units 70 provided with subject-matter designations; said guide-system being characterized by main-guides each respectively displaying a letter of the alphabet in an indexing position and displaying respectively, in a separate indexing position, the leading decimal component of a three-digit index-number coded from said alphabetical index to the subject-matter designations, and sub-guides displaying respectively succeeding decimal components of said index-numbers, with the hundreds, tens and units-digit components respectively aligned in neighboring rows, to permit said decimal components to be read in continuity from one row to another to yield 80

90 the respective index-numbers.

12. A system of guides for record-files of the class having subject-matter units provided with subject-matter designations; said guide-system being characterized by guides 95 respectively displaying, in a set of three adjacent, offset indexing positions, the hundreds, tens and units-digit decimal components of three-digit index-numbers severally coded from said subject-matter designations, and 100 readable in continuity from row to row in said set, the said hundreds-digit and tens-digit decimal components being respectively written with ciphers to aid the eye in locating complementary components in adjacent 105 rows in which they are at considerably different distances from the user.

13. A system of guides for filing-systems, said guides each respectively displaying a letter of the alphabet in an indexing position 110 offset from that of neighboring guides, and displaying respectively in a separate indexing position the hundreds-digit decimal component of an index-number.

14. A system of guides for filing systems, 115 said guides each respectively displaying a letter of the alphabet in an indexing position offset from that of neighboring guides, and displaying respectively in a separate indexing position the hundreds-digit decimal component of an index-number, said decimal-component positions being in alignment.

15. A system of guides for indexing record-files of the class having subject-matter units 120 provided with subject-matter designations; said guide-system being characterized by main-guides each respectively displaying a letter of the alphabet in an indexing position

and displaying respectively, in a separate indexing position, the leading decimal component of an index-number derived from said subject-matter designation, according to a code substantially as follows:

ABC	DEF	GHI	JKL	MNO
1	2	3	4	5
PQR	STU	VWY	XZ	

10

6	7	8	9

16. A system of guides for indexing record-files of the class having subject-matter units provided with subject-matter designation; said guide-system being characterized by main-guides each respectively displaying a letter of the alphabet in an indexing position and displaying respectively, in a separate position, the leading decimal component 15 of a three-digit index-number derived from said subject-matter designations according to a code substantially as set forth in claim 15.

17. A system of guides for filing systems, said guides each respectively displaying a letter of the alphabet in an indexing position, and displaying in a separate indexing position a hundreds-digit decimal component of an index-number derived from said alphabetical index according to a code substantially as 20 follows:

ABC	DEF	GHI	JKL	MNO
100	200	300	400	500
PQR	STU	VWY	XZ	

85

600	700	800	900

18. A guide for filing systems, said guide displaying a letter of the alphabet in an indexing position, and displaying in a separate position a hundreds-digit component of an index-number derived from said alphabetical index according to a code substantially as set forth in claim 17.

19. A record-filing system comprising as 45 elements subject-matter units provided with subject-matter designations and with a plurality of series of three-digit filing-numbers coded from said designations; said filing system comprising as other elements guides bearing respectively a decimal component of one of a plurality of series of three-digit index-numbers.

20. A system of guides for indexing record-files of the class having subject-matter units provided with subject-matter designations; said guide-system being characterized by main-guides each respectively displaying a letter of the alphabet in an indexing position and displaying respectively, in a separate indexing position, the leading decimal component of a primary index-number, and sub-guides each respectively displaying a succeeding decimal component of said primary index-number, and other sub-guides 60 each displaying respectively a decimal com-

ponent of secondary, tertiary or quaternary index-numbers.

21. A system of guides for indexing record-files of the class having subject-matter units provided with subject-matter designations; said guide-system being characterized by main-guides each respectively displaying a letter of the alphabet in an indexing position, serving to index said subject-matter units alphabetically, and each dis-

70

75 displaying respectively, in a separate indexing position, the hundreds-digit decimal component of a primary index-number coded from said subject-matter designations; and sub-guides displaying in offset positions the tens-digit and units-digit decimal components respectively of said primary index-number, to be read in continuation of said hundreds-digit component as a complete three-digit index-number forming one of a primary series serving to sub-divide numerically the units of matter already arranged alphabetically; and other sub-guides constituting

80

85 a secondary series, a tertiary series and a quaternary series respectively, each series comprising three-digit index-numbers also coded from said subject-matter designations, and so characterized as to distinguish the guides of each series from the guides of its predecessor, the secondary guides serving to subdivide subject-matter units already subdivided by the primary index-numbers, and the tertiary guides serving to subdivide, still further, the subject-matter units already subdivided by the secondary guides, while the quaternary guides provide the means for still further subdivision of the subject-matter units divided and subdivided as above indicated.

- said decimal components, with distinguishments.
24. A system of guides for record-files of the class having subject-matter units provided with subject-matter designations; said guide-system being characterized by guides respectively displaying in plural sets of rows, each set comprising three adjacent offset indexing positions, the hundreds, tens and 10 units-digit decimal-components of three-digit index-numbers severally coded from said subject-matter designations and readable in continuity from row to row in each set, as whole three-digit numbers, certain of 15 said sets of rows containing plural series of said decimal components, with distinguishments of color.
25. A guide-system of the class described; comprising guides bearing three-digit index-20 numbers in plural series.
26. A guide-system of the class described; comprising guides bearing three-digit index-numbers in plural series, each of said guides displaying a decimal component of one of 25 said index-numbers.
27. A guide-system of the class described; comprising guides each displaying respectively a decimal component of a three-digit index-number constituting one of a plural series including primary, secondary, tertiary 30 and quaternary index-numbers; each of said three-digit index-numbers having a hundreds-digit component, a tens-digit component, and a units-digit component.
28. A guide-system of the class described; comprising guides each displaying respectively a decimal component of a three-digit index-number constituting one of a plural series including primary, secondary, tertiary 35 and quaternary index-numbers; each of said three-digit index-numbers having a hundreds-digit component, a tens-digit component, and a units-digit component; and said guides displaying distinguishments characteristic of said primary, secondary, tertiary and quaternary series, in conjunction with the several components of said index-numbers 40 respectively.
29. A guide-system of the class described; comprising guides each displaying respectively a decimal component of a three-digit index-number constituting one of a plural series including primary, secondary, tertiary 45 and quaternary index-numbers; each of said three-digit index-numbers having a hundreds-digit component, a tens-digit component, and a units-digit component; and said guides displaying colors characteristic of said primary, secondary, tertiary and quaternary series, in conjunction with the several components of said index-numbers 50 respectively.
30. A guide for filing-systems, said guide displaying a letter of the alphabet in an indexing position, and displaying in a separate 55
- indexing position a decimal component of an index-number.
31. A guide for filing-systems, said guide displaying a letter of the alphabet in an indexing position, and displaying in a separate 70 indexing position a decimal component of an index-number coded from said alphabetical index.
32. A guide for filing-systems, said guide displaying a letter of the alphabet in an indexing position, and displaying in a separate 75 indexing position a decimal component of an index-number derived from said alphabetical index according to a code substantially that set forth in claim 15.
33. A guide for filing-systems, said guide comprising a metal body-portion, an integral metal tab bearing an alphabetical index, and a separate integral metal tab bearing permanent numerical indicia.
34. A guide for filing-systems, said guide comprising a body-portion, and a plurality of tabs thereon, one tab bearing an alphabetical index, and a separate tab bearing complementary numerical indicia.
35. A guide for filing-systems, said guide comprising a body-portion, and a plurality of integral tabs thereon, one tab bearing an alphabetical index, and a separate tab bearing complementary numerical indicia.
36. A filing-member of the class described, said filing-member comprising a body-portion, and an integral, permanently inclined marginal portion, having an index formed 90 permanently in relief thereon.
37. A filing-member of the class described, said filing-member comprising a body-portion, and an integral, permanently inclined marginal portion bearing embossed numerical indicia.
38. A guide for filing-systems, said guide comprising a body-portion, and a plurality of permanently inclined integral tabs thereon.
39. A guide for filing-systems, said guide comprising a body-portion, and a plurality of 95 permanently inclined integral tabs thereon, one bearing alphabetical indicia and another bearing numerical indicia.
40. A record-filing system comprising aluminum guides having integral tabs inclined upwardly and rearwardly, relatively to the body-portion of said guides, and bearing permanent filing indicia.
41. A record-filing system comprising guides respectively constituted of relatively 115 indestructible material with indicia formed permanently thereon, in relief.
42. A record-filing system comprising guides respectively constituted of relatively 120 indestructible material embossed with indicia in relief.
43. A record-filing system comprising guides respectively constituted of relatively 125 indestructible material embossed with relief indicia in fields of contrasting colors.

44. A record-filing system comprising guides respectively constituted of relatively indestructible material embossed with relief indicia in fields of contrasting colors of enamel.
45. A record-filing system comprising guides constituted of relatively indestructible material, and provided with permanent indicia formed in fields of contrasting colors.
46. A record-filing system comprising guides constituted of relatively indestructible material, and provided with permanent indicia formed in fields of contrasting colors upon tabs borne thereby.
47. A record-filing system comprising guides constituted of relatively indestructible material, and provided with permanent indicia formed in fields of contrasting colors, upon tabs integral with the body-portion of said guides.
48. A record-filing system comprising guides respectively constituted of bright metal having tabs with indicia formed by displaying said bright metal in fields of contrasting color.
49. A record-filing system comprising aluminum guides having tabs bearing indicia displaying said aluminum in fields of contrasting colors.
50. A record-filing system comprising aluminum guides having tabs bearing indicia displaying said aluminum in fields of contrasting enamel.
51. A record-filing system comprising aluminum guides having tabs bearing indicia displaying said aluminum in fields of contrasting color.
52. The method of making stock guides for filing-systems by embossing metal blanks to form thereon complemental, alphabetical and numerical marginal indicia, removing portions of said indicia, bending the metal margins to display the remaining indicia at an angle to the bodies of said blanks, and coloring said margins.
53. A set of blanks for stock filing-guides, said set being constituted of blanks in nine series having thereon alphabetical and numerical indicia in substantially the following arrangement:—
A	B	C	100	10	1	100	10	1	55
D	E	F	200	20	2	200	20	2	
G	H	I	300	30	3	300	30	3	
J	K	L	400	40	4	400	40	4	
M	N	O	500	50	5	500	50	5	
P	Q	R	600	60	6	600	60	6	
S	T	U	700	70	7	700	70	7	
V	W	Y	800	80	8	800	80	8	
XZ			900	90	9	900	90	9	60
54. A set of blanks for stock filing-guides, said set being constituted of blanks in nine series having thereon alphabetical and numerical indicia in substantially the following arrangement:—
A	B	C	100	10	1	100	10	1	70
D	E	F	200	20	2	200	20	2	
G	H	I	300	30	3	300	30	3	
J	K	L	400	40	4	400	40	4	
M	N	O	500	50	5	500	50	5	
P	Q	R	600	60	6	600	60	6	
S	T	U	700	70	7	700	70	7	
V	W	Y	800	80	8	800	80	8	
XZ			900	90	9	900	90	9	75
55. A set of blanks for stack filing-guides, said set being constituted of blanks in nine series having thereon alphabetical and numerical indicia in substantially the following arrangement.

A	B	C	100	10	1	100	10	1	100	10	1
D	E	F	200	20	2	200	20	2	200	20	2
G	H	I	300	30	3	300	30	3	300	30	3
J	K	L	400	40	4	400	40	4	400	40	4
M	N	O	500	50	5	500	50	5	500	50	5
P	Q	R	600	60	6	600	60	6	600	60	6
S	T	U	700	70	7	700	70	7	700	70	7
V	W	Y	800	80	8	800	80	8	800	80	8
XZ			900	90	9	900	90	9	900	90	9

Signed at New York, in the county of New York, and State of New York this 5th day of September, 1923.

CHESTER I. WAGNER.
